UNITED STATES PATENT OFFICE.

GEORGES GANGLOFF, OF GENEVA, SWITZERLAND.

COACH-WORK COLUMN OF VEHICLES.

Application filed November 19, 1925, Serial No. 70,074, and in Switzerland November 27, 1924.

This invention relates to the coach work columns of vehicles, for instance of motor cars.

According to this invention a column is divided into two portions, one directly secured to the chassis and the other quite separate from the first and adapted to be removably secured thereto, these parts and their means of attachment being so arranged that the second said part can be placed as a prolongation of the first and there secured if the coach work is to be closed, whether partially or wholly, or be housed within the first part and there secured when the coach work is to be open.

The invention is illustrated in the accompanying drawing as applied to a transformable coach work of motor car, that is a coach work which may sometimes be partially or wholly closed and at other times be open.

In said drawing:

Fig. 1 is an elevation of a column;

Fig. 2 is a part vertical section taken at right angles to the elevation shown in Fig. 1;

Fig. 3 is a horizontal section; while

Fig. 4 is a side elevation of the lower end of the upper section of a column.

Fig. 5 is a top view of the lower end of the upper section of a column.

Fig. 6 is a side view of the joint between the upper and lower sections of a column.

Fig. 7 is an end view of the joint between the upper and lower sections of a column.

Fig. 8 is a side elevation of the upper end of the lower section of a column.

Fig. 9 is a top view of the upper end of the lower section of a column.

Fig. 10 is a side view of a clamping plate used to lock the two column sections together.

Fig. 11 is a top view of a clamping plate.

Fig. 12 is a partial longitudinal sectional view of the upper section telescoped in the lower section of a column.

The invention as applied to a motor car comprises two identical columns each consisting of two parts 1, 2 (Figs. 1 to 3), each column being directly secured to one of the side members 3 of the chassis, but not to the frame of the coach work, and each of which carries double hinge members 4 which support doors 5, 6, such doors being to the right and left of each column for giving access to the front and rear seats in the vehicle; in

the doors are housed vertically movable panels 40, 41. Columns 1, 1, are connected one to the other by transverse members 7, 8.

Each part 1 is of cylindrical tubular shape, and its lower end engages in a socket 10 of a square support 11, the said part 1 having brazed thereto a stirrup 14 resting on a similar stirrup 12 on support 11, the stirrups 12 and 14 being connected by bolts and nuts 13. The support 11 has also a base 15 supporting the socket 10 and a foot 16 resting upon side member 3 of the chassis; foot 16 is secured to member 3 by bolts and nuts 17 and also by a stirrup 18.

Each portion 2 (see Figs. 1 to 7) of the column is in transverse section a double T its outer faces 20 are rounded while grooves 19 of trapezoidal section serve as guides to panels 40, 41, the said grooves 19 being provided with flat springs 21 for preventing the panels 40, 41 from rattling. Portion 2 is provided at one end with a horizontal foot 22 strengthened by a rib 24 and adapted to pass between two hook-like lugs 23 on the portion 1 of the column and to encounter an abutment 25 thereon. Foot 22 is maintained in position by a clamping plate 26 which also passes between the lugs 23 and which is provided with a screw 27 resting against the foot 22. In this foot are formed trapezoidal notches 28 to provide clearance for the hinge side of the doors when the upper section 2 is telescoped within the lower section 1, as shown in Fig. 12.

The arrangement operates as follows:

When it is desired that the coach work should be completely closed (by the side walls and roof) or when it is desired that it should be partially closed (by the side walls, but not by the roof), the portion 2 is placed upon portion 1 of which it forms the prolongation (see Figs. 1, 2, 6 and 7) by its foot 22 being passed between lugs 23 until it comes against the abutment 25; then it is secured by means of clamping plate 26 inserted beneath lugs 23 and there locked by a screw 27. The panels 40, 41 slide, in the closed position of the doors, in grooves 19.

If it be desired to open the coach work, the roof is lifted, portion 2 separated from portion 1 by removing clamping plate 26, the said portion 2 being reversed and introduced into part 1 and there secured by clamping plate 26 (see Fig. 12). Portion 2 of the column can thus be carried by the

vehicle in a position where it is readily available when desired and where it does not reduce the carrying capacity of the vehicle.

In this manner the length of the column 5 may be varied.

If necessary column 1—2 may be removed by merely unscrewing nuts 13 maintaining it in the support 11.

Part 2 may be constituted by the foot 10 22, a metal tube integral with the foot and a lining of rubber having a cross section of double T shape.

The column 1—2 may be secured to the chassis in any other manner provided that 15 it is directly secured thereto. The securing of portion 2 on portion 1 in one or other of its positions may be effected in other manners besides that illustrated.

The column may also be applied to a 20 non-transformable coach work of a vehicle.

What I claim is:

1. In a vehicle coach work column the combination of two portions, the second of 25 which is separable from the first and is adapted to be removably secured thereto, attachment means for securing both portions to one another, whereby the said second portion can be placed in position either as a prolongation of the former and there secured, or can be housed within the former and there also secured, said attachment means comprising a foot at one end of the second portion, lugs at the upper end of the first portion between which the foot is 30 adapted to pass in either of its two positions, and a clamping member by means of which the foot may be secured.

2. In a vehicle coach work column the combination of two portions, the second of 40 which is separable from the first and is adapted to be removably secured thereto, attachment means for securing both portions

to one another, whereby the said second portion can be placed in position either as a prolongation of the former and there secured, or can be housed within the former and there also secured, said attachment means comprising a foot at one end of the second portion, lugs at the upper end of the former portion between which the foot is 50 adapted to pass in either of its two positions, and a clamping plate by means of which the foot may be secured, said clamping plate being arranged so as to pass between the foot and the lugs, so that it is supported thereon, and being provided with a screw allowing the foot to be clamped against the first portion of the column.

3. In a vehicle coach work column the combination of two portions, the second of 60 which is separable from the first and is adapted to be removably secured thereto, attachment means for securing both portions to one another, whereby the said second portion can be placed in position either as a prolongation of the former and there secured, or can be housed within the former and there also secured, said attachment means comprising a foot at one end of the second portion, lugs at the upper end of the former portion between which the foot is 65 adapted to pass in either of its two positions, and a clamping plate by means of which the foot may be secured, said clamping plate being arranged so as to pass between the foot and the lugs, so that it is supported thereon, and being provided with a screw allowing the foot to be clamped against the first portion of the column, an 70 abutment being provided on one of the portions against which the foot contacts when 75 passed between the lugs.

In testimony whereof I affix my signature.
GEORGES GANGLOFF.
